[57] CLAIM

The ornamental design for a lighted make-up mirror, as shown and described.

DESCRIPTION

FIG. 1 is a front elevational view of a lighted make-up mirror showing our new design, the stand and the side mirrors being in their operative position;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front elevational view of the lighted make-up mirror, with the stand and the side mirrors in their folded position;

FIG. 8 is a rear elevational view of FIG. 7;

FIG. 9 is a left-side elevational view of FIG. 7;

FIG. 10 is a right-side elevational view of FIG. 7;

FIG. 11 is a top plan view of FIG. 7; and

FIG. 12 is a bottom plan view of FIG. 7.
